UNITED STATES PATENT OFFICE.

PAUL WARE, OF NEW YORK, N. Y., ASSIGNOR TO WARE RADIO, INC., OF NEW YORK, N. Y., A CORPORATION OF DELAWARE.

DUPLEX RADIO COMMUNICATION.

Application filed July 3, 1922. Serial No. 572,405.

This invention relates to duplex radio communication and has for its object to enable two stations each having separate receiving and transmitting elements at the same location to simultaneously communicate, without having the receiver paralyzed by the relatively powerful transmitter adjacent thereto. It is the practice in many of the systems in use at present to either widely separate the receiver and transmitter of a station of more than nominal power for simultaneous communication, or else to cut out one while the other is operating, which does not permit simultaneous communication.

By this invention only such separation of a few feet between transmitter and receiver as may be had in the same building is necessary in order to provide simultaneous communication over distances up to several hundred or more miles.

Other important objects of this invention are to improve upon the customary transmitting and receiving efficiencies, to eliminate the radiation of harmonics and to so increase the selectivity of the receiving apparatus that office to office radio communication between widely situated large cities, heretofore considered impracticable for many reasons, is now a practicable achievement.

It is found that the customary interference from other radio stations, and interferences and racket from induction customarily encountered in attempting to operate receiving stations in factory buildings, etc., in the centers of large cities is greatly minimized or removed altogether by the receiving arrangement hereinafter described.

It is also found by this invention that interference from atmospheric electricity or "static" is considerably minimized.

This invention consists essentially in transmitting continuous waves of one frequency from an elevated radiating system, while simultaneously receiving another frequency by means of a specially designed and constructed coil receiving set situated nearby.

I have found that the ordinary coil receiving set is inoperable in the proximity of a powerful transmitter, on anywhere near the same operating frequency, on account of paralysis of the receiving circuit by the adjacent transmitter. I have found, however, that a tuned coil receiving element

having as small an area as approximately one square foot, loosely coupled to a powerful high frequency amplifier and detecting means, where the entire receiving circuit excepting the small coil collecting element is properly shielded, is thoroughly workable in the same building where a powerful transmitter is operating and on very nearly the same operating frequency as that of the transmitter. I have found moreover that such a receiving circuit when properly designed is much more selective and possesses greater overall sensitiveness than is customarily found in radio receiving systems. An electrostatic shield surrounding the small coil element will permit of still closer physical and frequency operation. Positioning of the coil element with respect to the transmitting system, that is, with a flat side towards the transmitter, also tends to permit of closer operation, but the selectivity of this receiving system is such that when operated in connection with a transmitting equipment having the characteristics described herein, no critical positioning is found to be necessary. In fact under quite usual operating conditions it is found that the receiving coil may be pointed directly at the transmitter antenna lead-in, but there is obviously advantage in not doing this. The coil should, of course, point approximately towards the distant communicating station for best reception.

Almost any type of transmitter may be used, but a preferred form of highly efficient master oscillator circuit employing vacuum tubes is shown herein.

The invention will be more fully understood in connection with the description of the accompanying drawings wherein:

Fig. 1 is a general diagram,

Fig. 2 is a diagram of the transmitting circuit,

Fig. 3 is a diagram of a receiving circuit.

Fig. 4 is a partial resonance curve of an ordinary type of receiver,

Fig. 5 is another portion of the curve of Fig. 4, and

Fig. 6 is a resonance curve of a receiver according to this invention.

Referring to Fig. 1, 1 represents the elevated transmitting antenna supported by masts 2, the lead-in 3 passing through insulator in the roof 15 of the building 14, to

transmitting unit 4. Transmitting ground connection is made at 5. 6 represents the coil receiving set, complete. 12 are telephone receivers and 13 is a knob by which the receiving operator if he desires may adjust the pitch of his incoming signal. 11 represents a metallic sheathed grounded cable containing several conductors by which the transmitter is automatically controlled from the operating position 9, 10, where 9 specifically indicates a switch for turning off and on the transmitter and 10 indicates a common wire telegraph key with side lever.

15 Most any type of transmitting circuit may give satisfactory results, but the employment of powerful vacuum tubes is preferred inasmuch as they are the most readily obtainable means for securing pure waves. Fig. 2 is a diagram of a transmitting circuit which gives excellent results in this system. Referring to the figure, the left hand tube MO and its accompanying circuit represents a master oscillator used to drive the two right hand power amplifier tubes PA, and to set the frequency of the transmitted waves and maintain their frequency constant independently of changes in the antenna circuit constants. 7 represents five different high frequency choke coils, 8 are three blocking condensers while 18 are grid-leak resistances. 16 are gridplate oscillation condensers in the master oscillator circuit, and 17 is a variable inductance. 19 is a condenser the size of which varies the amount of excitation which the master oscillator imparts to the power amplifiers. 20 are ammeters for indicating the plate current to the power amplifier tubes and 21 is a variable choking unit for the purpose of suppressing undesirable oscillations at this point, and which greatly increases the customary efficiency of such a circuit. 22 is an A. C. generator for furnishing filament heating current. 23 is a potentiometer across the generator having a central or neutral point, which constitutes the "ground" of the circuit. From this neutral point to both sides of the filaments are condensers of equal size for passing high frequency by potentiometer 23 to each side of the filaments equally. This method not only effectively removes the A. C. "hum" from the emitted waves but also lengthens filament life by equalizing the current to each side of the filament. 24 is an A. C. voltmeter across the filaments which is a better filament indicator for this circuit than a series ammeter. 25 is a high voltage D. C. generator having its armature skewed slotted about three-quarters of its slot pitch. This skew slotting in connection with a properly designed filter 26 consisting of inductances with condensers on each side is a very effective means for removing generator ripple. The negative terminal of 25 is connected to the neutral point on 23 while the positive terminal connects to the plate circuits of the three tubes as shown. The antenna circuit comprises the aerial 30, the ammeter 31, the secondary 28 of a power output transformer, the antenna tuning inductance 29, and a key-click eliminator circuit 34, 35, 36, all of which are connected in series and grounded at 5. This circuit is coupled to the power oscillator 75 through the primary 27 of the power output transformer. And the primary is so designed that if the antenna circuit is opened, the plate current consumed by the power amplifiers drops to a very low value. This is accomplished by making its inductance, in connection with the tube and circuit capacity in parallel with it, such that the primary circuit will choke or approximately choke over the adjustable wave-length range of 85 the transmitter. When the antenna circuit is closed, however, and is brought into resonance with the frequency of the master oscillator, this choking effect in the primary is destroyed, the primary and secondary 90 then acting like a power transformer. This transmitting circuit gives quiet transmission on constant frequency, without harmonics, and there is no hum due to dynamo ripple when tuning a receiver near the transmitter. 95 A dial on variable inductance 17 may be calibrated to indicate directly the frequency on which the transmitter is operating. For any setting of 17 therefore, the plate current to both the power amplifier tubes may be adjusted to the desired value by the coupling between 27 and 28 when 29 is adjusted so that the antenna is in tune with the master oscillator. For maximum plate circuit efficiency it is essential that primary coil 27 be 100 designed to have the lowest possible distributed capacity, inasmuch as when the antenna circuit is brought into resonance such capacity would act as a shunt and cause a loss in power. After these adjustments are made, a substantial increase in efficiency may be had by adjusting the resonant circuit 21. It is found that a variable choking means at this point offers a considerable improvement over a fixed choke, inasmuch as the frequency of the undesirable oscillations is found to differ with different settings of 17. Feeding the high voltage plate supply in parallel as shown, instead of in series with the voltage of the high frequency oscillations across 27, reduces the maximum high potential on the tubes and thus higher than rated D. C. potentials may be employed. The circuit just described enables vacuum tubes to be run continuously at from two and one half to three times their rated outputs. It is found that plate circuit efficiencies for the power amplifier tubes of 75 per cent is readily obtainable, and the overall efficiency of such a circuit is well above 105 110 115 120 125 130

that of arc or spark transmitters. Vacuum tubes which have been especially designed to withstand high plate potentials have been found to give high plate circuit efficiencies and if used in this circuit would yield even better results than those enumerated.

The generators 22 and 25 may be direct connected on the same shaft with a driving motor 33 as indicated by the dotted line. In Fig. 1 such a motor generator would be included in 4 together with an automatic starter controlled through the grounded cable 11 from the operating position by switch 9, so that the closing or opening of 9 automatically turns on or off the previously adjusted transmitter.

Keying for telegraphy is from 10 as indicated in Fig. 1, also through the sheathed cable 11, and may be accomplished in any suitable manner which does not create an audible clicking in the receiving system. A satisfactory method, referring again to Fig. 2, is by inserting condenser 35 bridged by resistance 36 in the ground lead as shown, and having such proportions that when relay 34, controlled through a battery from key 10, is opened the current in 31 drops to zero, and very little sparking if any occurs at the relay contacts during transmission of signals.

The enclosing in grounded metallic sheathing 11 of all conductors passing between the transmitting and receiving circuits prevents direct carriage of transmitter high frequency energy along these conductors. What stray transmitter high frequency energy passes along other adjacent metallic objects, such as gas pipes, electric conduits, etc. I believe to mostly affect the receiving coil circuit by electrostatic coupling, inasmuch as the electrostatic shielding, already referred to, removes the difficulty.

The preferred receiving circuit for this system is shown in Fig. 3, where 37 is the small receiving coil, movably directionally mounted, 38 an electrostatic shield, and 51 is the coil tuning condenser. 42 represents a metal box completely surrounding the remainder of the receiving equipment. 39 are radio frequency amplifiers, 40 a detector and 41 tone amplifiers. The shield 38 is connected to 42 as well as is one side of the filament heating battery shown. The resonant loop circuit is loosely coupled by condenser 47 to the input resonant circuit 45 of the high frequency amplifier. The output tuned circuit 46 of the amplifier is then loose coupled by condenser 48 to the input tuned circuit 49 of detector tube 40. Condensers 47 and 48 are completely shielded by partitions 45 of the metal box 42 to prevent any possible coupling between the circuits excepting by capacity coupling through the condensers as intended. The high frequency trans-

formers are designed to give maximum amplification over the adjustable wave length range of the receiving set and are shielded by small metal boxes 43 which are also grounded to the box 42. Internal oscillations in the high frequency amplifier are prevented by bringing all of the grid connections to the potentiometer 44, which is bridged across the paralleled filaments. If the coils of resonant circuits 45 and 46 are so situated within the box that there is any chance for coupling between them they should be mounted opposing each other. Referring to the detector, coil 50 is mounted to give variable coupling with the inductance of 49 so as to give regenerative or beat-note reception, condenser 52 being to by-pass the high frequency by transformer and battery as shown. The tone amplifiers are transformer coupled in the usual manner, but transformer 53 is for the purpose of excluding D. C. plate current from the telephone receivers 12 for the purpose of eliminating key-click, as disclosed in my Patent 1,648,835, dated Nov. 8, 1927, entitled Two-way radio communication system, if it is desired to operate the system "break-in," as described in patent to Ware No. 1,379,144, instead of full duplex. The condenser 6 of tuned circuit 49 of the detector has the external adjustment indicated at 13 in Fig. 1 and may be desirable as a beats pitch regulator if this type of reception is used. The remainder of the circuit is self-explanatory. It is necessary that the metallic box 42 have good conductivity, which can be secured by using thicker metal if poor conductors are used. The holes through which the conductors to the coil aerial and head phones are brought out of the box 42 should be no larger than necessary.

To adjust this circuit to a given transmitting station the condensers 47 and 48 are first made quite large. This so broadens the frequency range of the circuit as to permit of rough tuning by condensers 51 and 6 at the same time. To make a final adjustment, however, and to secure the maximum selectivity the coupling is made very loose by condensers 47 and 48 and the tuned circuits of the loop, 45, 46 and 49 are then readjusted to be exactly in resonance with the incoming signal. Quite strong local oscillations in the detector circuit are found desirable for beats reception as this still further increases the selectivity. The probable reason for this is that spark interferences and other noises do not remain in phase with the local oscillations, which are too strong to be affected and are consequently reduced in loudness to a greater extent than is the beat note by increasing the strength of the local oscillations. The design of resonant circuits and the purity and degree of coupling between them is very vital in a receiver of this character and intended for duplex service. The ratio of in-

ductance to resistance of each resonant circuit should be as high as possible while the coupling should be either purely magnetic, or purely electrostatic as shown, between the 5 various resonant circuits, electrostatic coupling being preferred.

The receiving set just described has an overall sensitiveness probably equal or better than any practical receiving system in regular service, notwithstanding the diminutive 10 dimensions of the collecting element 37, which is preferably one foot in diameter for duplexing with a transmitter in the same room. I have found that such a receiver 15 operates without interference from a $\frac{1}{4}$ k. w. transmitter at a distance of 35 ft. on a 10% difference in operating frequencies between the receiver and transmitter.

This receiver is also found to be operable 20 in locations considered very undesirable or even unworkable for long distance reception, as for instance in factory buildings or other locations where there is considerable induction. This is because of the fact that no 25 external influence can affect the receiving equipment, except via the loosely coupled resonant element 37, 51.

It is found that while ordinary loose 30 coupled receivers will apparently exclude all but a narrow band of frequencies, see curve A, that upon close inspection, see curve B, such sets do pass frequencies over quite a wide range although in comparatively infinitesimal amplitudes. Receiving sets now 35 in use pick up sufficient energy on inside coils and even on battery leads, etc. passing away from the set box to make exclusion of strong interfering signals and other noises on frequencies widely differing from that to which 40 the set is adjusted impossible. Curve C is taken on a circuit like Fig. 3 with tighter than proper couplings at condensers 47 and 48. It was found at frequencies outside those 45 covered by the resonance curve that even a powerful transmitter in the same room would make no indication on a microammeter connected into the detector circuit.

Figures 4, 5 and 6 show "resonance curves" 50 obtained by plotting the value of current, in microamperes, in the detector circuit for a given tuning adjustment of the cycles per sec., of a nearby oscillator. In other words, the wave length of the nearby oscillator is varied from below the wave length for which 55 the receiver is tuned, through the wave lengths which cause resonance in the receiver circuit and beyond the point where resonance occurs. The peak of the curves in Figs. 4 and 6 show the wave length to which the receiver is tuned for best reception. Curve B, in Fig. 5, is a continuation of one side of curve A with the ordinate or current scale much enlarged. This curve shows that an unshielded receiving set will respond to wave 60 lengths considerably beyond that to which it

is tuned. This response has no effect on the head phones of the receiver when the transmitted waves are radiating a considerable distance away because of the small amount of radiated energy picked up by the aerial of the receiver, but when the receiver is located in the powerful field of the transmitting antenna, the energy picked up is sufficient to effect the head phones even when the receiving circuit is tuned to a different wave 75 length.

Under these conditions, it is difficult to exclude the strong signals from the local transmitting station and to receive weak signals from distant stations. Applicant has succeeded in overcoming this difficulty by adequately shielding the receiving set and connections thereto. This is strikingly shown by curve C in Fig. 6. This curve was plotted 80 from current indications read on a microammeter in the detector circuit of a receiving set constructed in accordance with applicant's invention and properly shielded. It will be noted that the curve on each side of the resonance frequency drops to zero, showing 85 that even when the shielded receiver is located in the powerful field of a local transmitting station, there is no current flowing in the detector circuit if the receiver is tuned to a wave length approximately 10% either 90 side of that of the local station.

Such a receiver is, therefore, highly selective and is adapted to pick up weak signals from distant stations even when the local station is transmitting on a wave length at 100 the limits noted above.

With transmitting and receiving equipment constructed and arranged as described, the operation of simultaneous duplex radio communication is greatly improved and simplified. 105

I claim:

1. A radio receiving system adapted for simultaneous operation with a nearby radio transmitter, and comprising in combination 110 a coil aerial in circuit with a radio frequency amplifier, a detector, and signal indicating apparatus, means for narrowing the upper part of the resonance curve of the receiving system including loose coupling between said coil aerial, radio frequency amplifier and detector, and means, including closed circuited metallic shields enclosing said amplifier, detector and loose coupling, for causing the lower part of said resonance curve to come 115 substantially to zero a predetermined distance to either side of the resonant frequency, whereby the said receiving system will be substantially unaffected by oscillations from the nearby transmitter having a 120 frequency outside those covered by said resonance curve.

2. A radio receiving system adapted for simultaneous operation with a nearby radio transmitter, and including a coil aerial in 125

- circuit with a radio frequency amplifier, a detector and signal indicating means, means for narrowing the upper part of the resonance curve of the receiving system including adjustable capacity coupling between said coil aerial, amplifier and detector, and means, including an electrostatic shield enclosing said coil aerial and closed circuited metallic shields enclosing said amplifier, detector, and capacity coupling in separate compartments, for causing the lower part of said resonance curve to come substantially to zero a predetermined distance to either side of the resonant frequency, whereby the said receiving system will be substantially unaffected by oscillations from the nearby transmitter having a frequency outside those covered by said resonance curve. 5 65
3. In a radio receiving system adapted for simultaneous operation with a nearby transmitter, a coil aerial in circuit with a tuning condenser, means for electrostatically shielding said aerial and its tuning circuit, radio frequency amplifying means loosely coupled to said coil aerial, a closed circuited metallic shield enclosing said amplifying means and said coupling in separate compartments, detecting and audio frequency amplifying means loosely coupled to said radio frequency amplifying means, a closed circuited metallic shield enclosing said last-named coupling and said detecting and audio frequency amplifying means in separate compartments, whereby to confine the resonance of said receiving system to a narrower band of frequencies. 20 70
4. In a duplex radio communication system having a transmitter and a receiver adapted for simultaneous operation on frequencies differing slightly from each other, comprising in the receiver the combination of a receiving element, amplifying and detector circuits, loose couplings between the receiving element, amplifier and detector circuits, an electrostatic shield for the receiving element, separate closed circuited shields enclosing the amplifying and detecting circuits and a source of power and conductors therefore within certain of said shields. 40 75
5. A radio receiving system comprising in combination a loop receiving element, a radio frequency amplifier and a detector, a loose coupling between the loop and the amplifier, a second loose coupling between the amplifier and detector, and shielding means enclosing the amplifier, the detector and the couplings. 50 80
6. In a duplex radio communication system, in combination, a transmitter having a radiating antenna, a master oscillator and power amplifiers, means for setting the frequency of the transmitted waves and means for maintaining the frequency of said waves constant independently of changes in the antenna circuit constants, a receiving set having a coil aerial, radio frequency amplifiers and a detector, means for coupling and shielding said aerial, amplifiers, and detector of the receiving set in such manner as to reduce the band of frequencies to which said set may respond for a given tuning adjustment whereby to permit duplex operation on a slight difference in the resonant frequencies of said transmitter and receiver. 10 85
7. A radio receiving system comprising an antenna unit, a radio frequency amplifier unit, and a detector unit, loose capacity couplings disposed between said units, a closed circuited metallic shield enclosing all of said units except the antenna. 15 90
8. In a radio receiver having an antenna unit, a radio frequency amplifier unit and a detector unit, the combination of loose capacity coupling means between said units to narrow the upper part of the frequency response curve and shielding means enclosing all parts except the antenna to cause the lower part of said curve to drop substantially to zero a predetermined distance on either side of the peak of the curve. 25 95
9. A radio receiving system comprising an antenna, a multi-stage radio frequency amplifier having means for controlling and maintaining regeneration, a detector, audio amplifier and signal indicating apparatus, said radio frequency amplifier and detector including a plurality of resonant circuits, closed circuited metallic shields enclosing all parts carrying radio frequency currents except the antenna, and coupling means disposed between the various portions of the circuit for narrowing the radio frequency response characteristic of the system. 30 100
10. A system for radio reception, comprising in combination an antenna, a radio frequency amplifier, potentiometer means therein controlling regeneration, a detector, an audio amplifying and signal indicating apparatus, closed circuited metallic shields enclosing all parts carrying radio frequency currents except the antenna, and successively disposed coupling means also within said shields for further narrowing the band of frequencies to which the system will respond. 45 105
11. A system for radio reception, comprising in combination an antenna, a radio frequency amplifier, adjustable regeneration means associated therewith, a detector, independent adjustable regeneration means associated therewith, an audio amplifying and signal indicating apparatus, closed circuited metallic shields enclosing all parts carrying radio frequency currents excepting the antenna, and successively disposed coupling means also within said shields for further narrowing the band of frequencies to which the system will respond. 55 110
12. A system for receiving continuous 60 115
- 65 120
- 70 125

- wave telegraph signals comprising an antenna, a radio frequency amplifier, potentiometer means therein for preventing internal oscillations and an adjustable oscillating detector, an audio amplifying and signal indicating apparatus, shielding means separately enclosing all parts of the apparatus excepting the antenna and coupling means disposed between the several portions 5 of the apparatus for narrowing the radio frequency response characteristic of the system.
13. A system for receiving continuous wave telegraph signals, comprising an antenna, a radio frequency amplifier, potentiometer means therein for preventing internal oscillations and an adjustable oscillating detector, an audio amplifying and signal indicating apparatus, shielding means enclosing all parts of the apparatus excepting the antenna and coupling means disposed between the several portions of the apparatus narrowing the band of frequencies to which the system will respond.
14. A duplex radio system comprising a loop receiving apparatus and a separately excited power amplifier vacuum tube transmitting apparatus, the loop being partially shielded the receiving apparatus being completely shielded and containing a radio frequency amplifier and a plurality of loose couplings, the transmitting apparatus containing an adjustable chocking means in series with the grids of the power amplifier tubes.
15. A duplex radio system comprising a loop receiving apparatus and a separately excited power amplifier vacuum tube transmitting apparatus, the receiving apparatus being completely shielded and containing a radio frequency amplifier and a plurality of loose couplings, the loop being partially shielded and having an area of approximately one square foot.
16. In combination with a radio receiving system having a collecting element, a radio frequency amplifier in circuit therewith, means for preventing internal oscillations in said amplifier, a detector and signal indicating means, and means for increasing the selectivity comprising means for narrowing the frequency response curve, and shielding means for excluding undesired strong signals.
17. In combination with a radio receiving system having a collecting element, a radio frequency amplifier in circuit therewith, means for preventing internal oscillations in said amplifier, a detector and signal indicating means, and means for increasing the selectivity comprising means for narrowing the frequency response curve, and shielding
- means preventing pick-up of signals excepting by way of said collecting element.
18. In combination with a radio receiving system having a resonant collecting element, a radio frequency amplifier in circuit therewith, means for preventing internal oscillations in said amplifier, a detector and signal indicating means, and means for increasing the selectivity comprising means for narrowing the frequency response curve, and shielding means for excluding undesired strong signals.
19. In combination with a radio receiving system having a collecting element, a radio frequency amplifier in circuit therewith, means for preventing internal oscillations in said amplifier, a detector and signal indicating means, and means for increasing the selectivity comprising a plurality of resonance and coupling means for narrowing the frequency response curve, and shielding means for excluding undesired strong signals.
20. In combination with a radio receiving system having a collecting element, a radio frequency amplifier in circuit therewith, means for preventing internal oscillations in said amplifier, a detector and signal indicating means, and means for increasing the selectivity comprising a plurality of resonance and coupling means for narrowing the frequency response curve, and shielding means preventing pick-up of signals excepting by way of said collecting element.
21. A system for receiving continuous wave telegraph signals, comprising an antenna, a radio frequency amplifier, detector, and audio amplifying and signal indicating apparatus, means for providing independent oscillations enabling heterodyne reception, and means for increasing the selectivity comprising a plurality of resonant circuits within the apparatus for narrowing the band of frequencies to which the system will respond, and means shielding the said amplifier and detector.
22. A system for receiving continuous wave telegraph signals, comprising an antenna, a radio frequency amplifier, a detector, and audio amplifying and signal indicating apparatus, means for providing independent oscillations enabling heterodyne reception, and means for increasing the selectivity comprising a plurality of resonance and coupling means for narrowing the band of frequencies to which the system will respond, and means shielding the amplifier and detector.
- Signed at New York, in the county of New York and State of New York, this 30th day of June A. D. 1922.
- PAUL WARE.
